UNITED STATES PATENT OFFICE.

WILLIAM HENRY SAUVAGE, OF NEW YORK, N. Y., ASSIGNOR, BY MESNE ASSIGNMENTS, TO GOULD COUPLER COMPANY, OF NEW YORK, N. Y.

SLACK ADJUSTER.

Application filed October 17, 1921. Serial No. 508,152.

To all whom it may concern:

Be it known that I, WILLIAM H. SAUVAGE, citizen of the United States, residing at New York, in the county of New York and State of New York, have invented certain new and useful Improvements in Slack Adjusters, of which the following is a specification.

This invention relates to improvements in slack adjusters and more particularly to slack adjusters adapted to be used in connection with the truck brake rigging of railroad cars, although, of course, it is to be understood that certain features thereof are applicable to other types of brake rigging for use not only on railroad cars, but on locomotives as well.

One of the objects of the present invention is to provide a simple and practical slack adjuster mechanism, particularly adapted for use directly with the brake beams of car trucks and so associated and cooperating therewith as to provide a compact, reliable and efficient mechanism, as well as one which may be easily and inexpensively manufactured and assembled.

A further object is to provide a slack adjuster of the above general type, having relatively few parts which will not be likely to get out of order.

Other objects will be in part obvious and in part hereinafter pointed out in connection with the accompanying sheet of drawings forming part of this disclosure, and showing one of various forms embodying the invention, and wherein the corresponding reference characters denote similar parts.

In these drawings,—

Figure 1 is an elevational view, partly in section, showing such parts of the brake rigging and associated brake beam as is necessary to enable one skilled in the art to fully understand the invention;

Figure 2 is a plan view of the parts shown in Figure 1, partly in section; and

Figure 3 is a detail view, partly in section of the adjusting rod.

Referring now to the drawings in detail, 5 denotes a live lever connected at the point 6 by a pull rod 7 adapted to move in the direction of the arrow for applying the brakes. The lower end of this lever 5 has pivotally connected therewith at the point 8 a push rod 10. The opposite end of this

push rod may be connected with a dead lever in the usual manner or to a fixed support depending upon the type of brake rigging with which the slack adjuster is associated. In the usual four-wheel trucks, however, a co-acting dead lever is positioned adjacent the other brake beam of the truck, with the dead lever at the opposite end of the truck.

There is indicated at 11 the usual brake beam which is provided at its ends with the customary brake shoe heads and shoes for cooperating with the wheels in the well known manner. Illustration of these parts, however, has been omitted for the sake of clearness. This brake beam is provided with the customary brake beam tension member 12, which runs from the opposite ends of the brake beams and forms a brace to prevent bending of the brake beam on application. A strut 13 is interposed between the brake beam 11 and the brace member or tension member 12 to hold the parts in proper relative position. This strut, however, differs from the one now in general use inasmuch as it is provided with an elongated slot in which the slack adjuster push rod 14 is mounted, (Figure 3). This push rod is provided with a clevis end 15 embracing the central part of the live lever 5 through both of which passes a pintle or pivot pin 16 provided with a holding cotter 17. The brake beam strut is provided on its sides with slots 17 permitting the relative fore and aft movement of the pin 16, whereby the slack is taken up. Immediately below the push rod 14 is an adjusting rod 18 adapted to pass through openings in end walls 20 of the housing 21, provided with one or more take up dogs 22 and holding dogs 23. In the present case, only one dog 22 for each rod is shown, but obviously a plurality of dogs may be employed if circumstances deem necessary. The dog 22 is partially supported by the push rod 14 and is fulcrumed at 24. It is provided with a hole 95 at its lower end through which the adjusting rod 18 passes and is normally held in canted position by means of a compressed coil spring 25 normally urging the lower part of the dog 22 toward the left. Likewise the dog 23 is fulcrumed in a slot 26 in the housing 21 and is also provided with a spring 27 urging it to the position shown

105

where it bites and holds the push rod 14, against movement towards the left, but permits movement in the opposite direction.

The take up rod 18 is provided with a slotted opening or part 30, surrounding the live lever just below the pivot pin 16. At the right of the slot 30 is a projection 34 passing through a lug 35 on the beam 11. A cushion spring 36 is adapted to be compressed on application and aid in taking up the slack and restoring the parts to normal position. This spring 36 prevents creeping of the rod 18 during use or to the rattle and jar of the mechanism while the car is in motion and always insures the proper lost motion and clearance between the shoes and wheels.

The upper part of the live lever is provided with a rod 31 having a return spring 32 mounted thereon. The end of the rod 31 is fixed so that as the live lever moves to applied position, as indicated in dotted lines, this spring is compressed against a tap 29 and when the brakes are released this spring aids in restoring the parts to normal position.

The operation of the present device is substantially as follows:

On application of the brakes the live lever moves toward the left into the dotted position. If any excessive travel occurs exceeding that provided for by the play between the slotted member 30 and the lower part of the live lever, then the adjusting rod 18 is moved relatively towards the right, being free to slip through the dog 22. In this manner, the exact excess travel of the brake rigging is, one may say, temporarily recorded. When the brakes are released, the parts tend to return to the normal position shown in full lines under the action of the several return springs. The adjusting rod, however, is prevented from a return movement, that is, towards the left, by reason of the take-up dog 22, and the part of the slotted member 30 at the left of the lower part of the live lever acts as a stop or fulcrum and complete return movement of the live lever is effected by reason of the slot 17 along which the pintle or fulcrum pin 16 is forced to travel under the action of the return spring 32. In this manner, the push rod 14 is moved towards the right a distance corresponding to the distance the adjusting rod 18 was moved towards the right during the application of the brakes, these parts being free to move through the permanent take up and holding dog 23.

On the next application of the brakes, the push rod 14, being held from relative movement towards the left, the brake will be applied in the same manner and will continue to operate until further wear and tear upon the brake shoes and associated

parts causes lost motion to develop. When the slightest bit of excess travel, however, is discovered, the slack adjuster will automatically take up this wear in the manner described.

When it is desired to apply new brake shoes and restore the parts to the original position, that is, with the slack adjuster mechanism in the position shown in Figure 1, both dogs 22 and 23 are moved to a position at right angles to the rods with which they cooperate, whereupon both rods are free to move relatively towards the left to the new position.

From the above, it will be seen that the present invention provides a simple and practical slack adjuster, particularly adapted for use in connection with the truck brake rigging of railway cars and is so intimately associated with the brake beam as to permit the same to be easily and quickly applied to truck brake rigging now in general use without material modification or change in the parts. The slack adjuster is reliable and efficient in use and operation, and it is believed to accomplish among others all of the objects and advantages hereinbefore set forth.

I claim:

1. In a slack adjuster mechanism of the character described, in combination, a live lever, a brake beam, a strut upon which said lever is mounted, an adjusting rod and push rod associated with said brake beam strut and live lever, and holding means cooperating therewith whereby one is actuated on application of the brakes when excess travel occurs and the other is actuated on release of the brakes to eliminate excess travel.

2. In a slack adjuster mechanism of the character described, in combination, a live lever, a brake beam, a strut upon which said lever is mounted, an adjusting rod and push rod associated with said brake beam strut and live lever, holding means cooperating therewith whereby one is actuated on application of the brakes when excess travel occurs and the other is actuated on release of the brakes to eliminate excess travel, and a return spring associated with said parts for returning the same to normal position.

3. In a slack adjuster mechanism of the character described, in combination, a live lever, a brake beam, a strut upon which said lever is mounted, an adjusting rod and push rod associated with said brake beam strut and live lever, and holding means cooperating therewith whereby one is actuated on application of the brakes when excess travel occurs and the other is actuated on release of the brakes to eliminate excess travel, said holding means comprising dogs normally urged into biting

position with the rods with which they are associated.

4. In a slack adjuster mechanism of the character described, in combination, a live lever, a brake beam, a tension member, a strut interposed between the brake beam and the tension member, a live lever fulcrumed in said strut and having a movable fulcrum point, a push rod carrying said fulcrum point, an adjusting rod adapted to be actuated on excess travel of the live lever on application of the brakes whereby said push rod is actuated on release of the brakes to eliminate lost motion, and holding means associated with said adjusting rod and push rod.

5. In a slack adjuster mechanism of the character described, in combination, a live lever, a brake beam, a tension member, a strut interposed between the brake beam and the tension member, a live lever fulcrumed in said strut and having a movable fulcrum point, and a push rod carrying said fulcrum point, an adjusting rod adapted to be actuated on excess travel of the live lever on application of the brakes, whereby said push rod is actuated on release of the brakes to eliminate lost motion, holding means associated with said adjusting rod and push rod, said holding means including a housing and dogs in said housing, and springs coacting with said dogs normally holding them in canted position permitting a free movement of both of said rods relatively in one direction, but adapted to prevent movement in the opposite direction.

6. In a slack adjuster mechanism of the character described, in combination, a brake beam, a tension member, a strut interposed therebetween having a slotted aperture, a live lever pivotally mounted in said slotted aperture, a push rod associated with the live lever and adapted to move along the slots of said aperture, an adjusting rod positioned parallel to said push rod adapted to be actuated on excess travel of the live lever on application of the brakes, and holding means adapted to co-act with said adjusting rod for holding the same in its newly associated position, whereby said push rod is moved a corresponding amount on release of the brakes.

7. In a slack adjuster mechanism of the character described, in combination, a brake beam, a tension member, a strut interposed therebetween having a slotted aperture, a live lever pivotally mounted in said slotted aperture, a push rod associated with the live lever and adapted to move along the slots of said aperture, an adjusting rod positioned parallel to said push rod adapted to be actuated on excess travel of the live lever on ap-

plication of the brakes, and holding means adapted to co-act with said adjusting rod for holding the same in its newly associated position whereby said push rod is moved a corresponding amount on release of the brakes, said holding means including a housing and dogs fulcrumed in said housing co-acting with said rods.

8. In a slack adjuster mechanism of the character described, in combination, a brake beam, a tension member, a strut interposed therebetween having a slotted aperture, a live lever pivotally mounted in said slotted aperture, a push rod associated with the live lever and adapted to move along the slots of said aperture, an adjusting rod positioned parallel to said push rod adapted to be actuated on excess travel of the live lever on application of the brakes, and holding means adapted to coact with said adjusting rod for holding the same in its newly associated position whereby said push rod is moved a corresponding amount on release of the brakes, said holding means including a housing and dogs fulcrumed in said housing co-acting with said rods, and a rod connected with said live lever and a spring on said rod operating between the live lever and a fixed point adapted to be compressed on application of the brakes to restore the mechanism to normal position on release of the brakes.

9. In a slack adjuster mechanism of the character described, in combination, a live lever, a brake beam, a strut upon which said lever is mounted, an adjusting rod and push rod associated with said brake beam strut and live lever, and holding means cooperating therewith whereby one is actuated on application of the brakes when excess travel occurs and the other is actuated on release of the brakes to eliminate excess travel, and means associated with said adjusting rod adapted to prevent creeping and accidental loss of brake shoe clearance.

10. In a slack adjuster mechanism of the character described, in combination, a live lever, a brake beam, a strut upon which said lever is mounted, an adjusting rod and push rod associated with said brake beam strut and live lever, holding means cooperating therewith whereby one is actuated on application of the brakes when excess travel occurs and the other is actuated on release of the brakes to eliminate excess travel, and means associated with said adjusting rod adapted to prevent creeping and accidental loss of brake shoe clearance, said means including a cushion spring acting on said adjusting rod and reacting on the brake beam.

In testimony whereof I affix my signature.

WILLIAM HENRY SAUVAGE.
